MAIL RECEPTACLE WITH DOOR ACTUATED SIGNAL

Carl H. Sprick and Mervin J. Renquist,
Julesburg, Colo.

Application July 14, 1948, Serial No. 38,678

1 Claim. (Cl. 232—35)

1

This invention relates to an improved mail box for rural delivery.

It is an object of this invention to provide an improved mail box of the kind to be more particularly described hereinafter to facilitate the deposit and removal of mail by rural carriers and the box owner. Due to the structure and arrangement of the boxes presently in use, in many instances it is difficult, and often impossible, to open the box and reach within from an automobile or other vehicle. Such structure of the box requires that the carrier or others get out of the vehicle thereby causing a delay in the delivery of mail to others. With a box constructed according to this invention, the mail carrier or box owner may drive the vehicle extremely close to the box so that he may reach within it from the wheels. The closure swinging arrangement is such to provide for opening the box without the danger of an outwardly swinging door striking the vehicle.

Another object of this invention is to provide a rural delivery mail box having a signal flag which is automatically moved to a lowered position upon opening the closure of the box, thereby eliminating the requirement of the carrier to lower the signal after a delivery. In this manner two operations of the carrier's work are accomplished by one movement and therefore the carrier's work is greatly lessened and the entire delivery may be accomplished in better time.

Yet another object of this invention is to provide a mail box of this kind which is attractive in appearance, efficient in operation, simple in construction and economical to build.

With the above and other objects in view, our invention consists in the arrangement, combination and details of construction disclosed in the drawings and specification, and then more particularly pointed out in the appended claim.

In the drawings,

Figure 1 is a side elevation partly broken away and partly in section, of a rural mail box constructed according to an embodiment of our invention,

Figure 2 is a front end elevation,

Figure 3 is a front elevation with the closure removed,

Figure 4 is a longitudinal section taken on the line 4—4 of Figure 1,

Figure 5 is a vertical section taken on the line 5—5 of Figure 2,

2

Figure 6 is a fragmentary detail section taken on the line 6—6 of Figure 1.

Figure 7 is a fragmentary section taken substantially in the line 6—6, showing the closure removed from the body,

Figure 8 is a fragmentary section taken on the line 8—8 of Figure 1.

Referring to the drawings, the numeral 10 designates generally an improved mail box for rural mail delivery so constructed and arranged that the closure therefor may be moved to an open position by sliding the closure vertically relative to the main body of the box, thereby permitting the box to be positioned close to or adjacent to other boxes, or in a restricted area. As the closure slides vertically there is no necessity for providing additional space in the area adjacent the box for the disposition of the closure in its open position. With a box of this kind the mail carrier may approach very closely to the forward end of the box in his vehicle and place the mail within the box without danger of the closure for the box striking the vehicle or requiring him to stop a suitable distance from the box to permit the closure to be opened.

The box 10 is formed with a housing or body 11 open at the front end thereof. The body 11 is made of sheet metal or other suitable material which may be formed in any suitable configuration. The side walls 12 are parallel and vertically spaced apart at their lower end by a bottom wall or floor 14 and connected together at their upper end by an upwardly bowed or arched wall 15. A closure as 16 is swingably supported on the body 11 for closing the front open end thereof. The side walls 12 are substantially rectangular in shape and formed with an arched or curved forward end. The curvature of the forward edge of the side walls 12 is formed as an arc of a radius. The radius of the arc of the front edges of the side walls is determined from a point 17 on the side walls intermediate the length thereof.

The closure 16 is hingedly supported on the body 11 at the point 17 so that the closure 16 slidably engages the front edges of the side walls in the closed position thereof. The forward edge of the body 11 is formed with a flange as 18 which depends from the forward edge of the top wall 15 downwardly to a point slightly below the upper end of the forward edges of the side wall 12.

The flange 18 provides a weather seal and is adapted to engage over the upper edge of the closure 16. The closure 16 comprises a forward

plate as at 19, hingedly and swingably supported on the body 11 by a pair of rearwardly extending arms 20. The arms 20 are secured to the side edges of the forward plate 19 and extend rearwardly to the point 17 which determines the curvature of the front edge of the side wall. A rearwardly extending flange 21 is fixed to or formed on the side edges of the lower end of the plate 19 and provides an attaching means for securing the arms 20 to the plate 19.

Each of the arms 20 is formed of a flat strip of metal or other suitable material and is bent upon itself to the shape to be described. The arms 20 are formed with a central web as 22 which is triangular in configuration, having a curved front edge of the same curvature of the forward edge of the side walls 12. The side edges of the web 22 converge rearwardly to the point 17 from which the radius of the front edge of the walls 12 is determined.

A flange as 24 is bent outwardly from the side edges of the plate 22 to stiffen the arms throughout their length. A pin as 25 engages through the juncture of the rearwardly extending edges of the arm 20 for swingably supporting the arms and closure on the body 11. The forward edge of the web 22 is secured to the rearwardly extending flange 21 of the closure 16 by rivets 26 or other suitable fastening means. In this manner the closure 16 is swingably supported on the body 11 and slidably engages the forward edge of the side walls 12 in an open and closed position.

An upwardly extending flange as 27 is formed on the forward edge of the bottom wall 14 of the body 11 to provide a seal for the closure. The extreme upper end of the plate 19 is reverted at one point as indicated by the numeral 28 for forming a stop member engageable with the upper edge of the flange 27 for limiting the downward swinging movement of the closure about the pin 25. A spring-pressed latch as 29 is fixed to the lower edge of the bottom wall 14 at the forward end and is engageable with a bead as 30 on the lower edge of the plate 19 for resiliently supporting the closure 16 in a raised or closed position. A U-shaped handle as 31 is fixed on the forward side of the plate 19 at the upper end to provide a suitable handle for moving the closure 16 to the open or closed position.

A signal flag as 32 is rockably supported on the body 11 for indicating to the carrier that there is mail within the mail box to be picked up or for indicating to the owner that mail has been deposited in the box. The flag 32 is so constructed and arranged that it will be supported in its raised position by the arms 20 and upon opening of the closure for removing the mail will permit the flag 32 to be dropped. The flag 32 is fixed to the upper end of a supporting arm 34 which is pivotally mounted on the forward end of one side 12 of the body 11.

An elongated slot 35 is formed on the lower end of the arm 34 and a pivot pin 36 engages loosely in the slot 35. The pin 36 is fixed to the outer side of an attaching plate 37 which is adapted to be secured on the side wall 12 by rivets or other suitable fastening means. The pin 36 is fixed midway the length of the plate 35 and an outwardly extending arm as 38 is bent from the upper edge of the plate at the forward end thereof, forming a stop for limiting the forward swinging movement of the arms 34. In the raised position of the arms 34 and flag 32, the bottom edge of the arms 34 is adapted to press downwardly or

engage the upper side of the upper flange on the web 22.

A stop member 39 is fixed on the flange and limits the forward swinging movement of the arms 34 below the pivot 36 thereof. The flag 32 is made of metal or other substantial material and is normally disposed rearwardly of the pivot pin 36 in the raised position of the flag. In this manner the weight of the flag 32 will gravitatively bias the arms 34 for swinging downwardly and rearwardly to a position shown in dotted lines in Figure 1.

A spring-pressed clip as 40 is fixed to the inner side of one of the side walls 12 within the body 11 near the forward end thereof. The clip 40 is provided for supporting cards or other thin pieces of mail within the box near the forward end so that it will be unnecessary for the carrier or others to reach to the back end of the box to remove small articles.

In the use and operation of this box 10, the closure 16 will be normally closed and the flag 32 in its lowered position. For opening the closure it is necessary only to press the spring-pressed latch 29 rearwardly out of engagement with the bead 30 on the lower end of the plate 19. The weight of the plate 19 and arms 20 will cause the closure 16 to swing downwardly about the pivot pin 25. The stop member 28 will engage with the flange 27 on the bottom 14 to limit the downward swinging movement of the closure. At this time the mail may be deposited within the housing 11. The closure 16 is then raised to its closed position and the arm 34 which supports the flag 32 is moved rearwardly to position the pin 36 in the forward or lower end of the slot 35. The arm 34 may then be pivoted about the pin 36 to dispose the flag 32 in the raised position.

The forward swinging movement of the arm 34 to the raised position is limited by the stop member 39 and the arm 34 may then be lowered to position the pin 36 in the upper end of the slot 35. In this manner the lower end of the arm 34 will abut the stop member 39 carried by the flange of the arms 20 for supporting the flag 32 against inadvertent downward swinging movement about the pin 36. When the closure 16 is again opened to remove the mail from the body 11, the flange on the side arms will be lowered away from the lower edge of the bar 34. This will permit the free swinging movement of the flag about the pin 36 so that the flag will be gravitatively swung to the lowered position.

We do not mean to confine ourselves to the exact details of construction herein disclosed but claim all variations falling within the purview of the appended claim.

What we claim is:

A deposit and collection receptacle comprising a body formed of opposite sides, a top wall, a bottom wall and a rear end wall, the front end of said body being open and the forward edges of said side walls being convex, a downwardly swinging curved closure engageable over the front end of said body, a flange carried by said top wall and projecting downwardly a short distance along said side walls, the upper portion of said closure engaging on the inner side of said flange when said closure is in closed position, a pair of closure supporting arms fixed to said closure and extending rearwardly on the outer sides of said side walls to a point substantially adjacent the rear end wall and gravitatively swingable downwardly to closure opening position, means pivotally securing the rear ends of said arms to the

sides of said body, latch means carried by said bottom wall releasably engaging said closure for holding the latter in an upper closed position; a signal member including an elongated staff formed with an elongated opening adjacent the lower end thereof, means carried by one of said side walls engaging through said opening pivotally mounting said staff in a position whereby the lower end of said staff will engage one of said arms when the latter is raised, and a stop fixed to said one arm engageable by said staff for holding said staff vertical when said closure is in closed position.
